UNITED STATES PATENT OFFICE.

RALPH COHEN, OF BAYONNE, NEW JERSEY.

DESIGN FOR A MANTLE-HOLDER.

SPECIFICATION forming part of Design No. 34,804, dated July 16, 1901.

Application filed June 8, 1901. Serial No. 63,812. Term of patent 7 years.

To all whom it may concern:

Be it known that I, RALPH COHEN, a citizen of the United States, and a resident of Bayonne, in the county of Hudson and State of New Jersey, have invented and produced a new and original Design for a Mantle-Holder, of which the following is a full, clear, and exact description, reference being had to the accompanying drawing, forming a part thereof, in which is represented a perspective view of a mantle-holder embodying the features of my design.

The leading features of the design consist in the segmental body element A and an axial or transverse element B, extending inward from a terminal of the body element and terminating in a vertical hook C.

A minor feature of the design consists in a horizontal hook D at the opposite terminal of the body element, the hook D being inwardly directed.

Having thus described my invention, I claim as new and desire to secure by Letters Patent—

The design for the mantle-holder herein shown and described.

In testimony whereof I have signed my name to this specification in the presence of two subscribing witnesses.

RALPH COHEN.
